Atty's.

UNITED STATES PATENT OFFICE.

THEODORE BONROE, OF ST. LOUIS, MISSOURI.

SELF-CLOSING COCK OR FAUCET.

SPECIFICATION forming part of Letters Patent No. 514,879, dated February 13, 1894.

Application filed April 24, 1893. Serial No. 471,602. (No model.)

To all whom it may concern:

Be it known that I, THEODORE BONROE, of the city of St. Louis and State of Missouri, have invented certain new and useful Improvements in Self-Closing Cocks or Faucets, of which the following is a full, clear, and exact description, reference being had to the accompanying drawings, forming a part hereof.

My invention relates to an improved "cock or faucet" applicable for various uses, and consists in the novel construction, combination and arrangement of parts hereinafter described and designated in the claims.

The object of my invention is to provide an improved cock or faucet of the class known as "self-closing," which shall be very simple in construction, of low cost and immunity from disorder to a great degree during use.

In the drawings: Figure 1 is a sectional side elevation of a cock or faucet embodying my invention. Fig. 2 is a section on line X—X of Fig. 1.

1 indicates a fixed tubular portion of the shell, which may have its exterior tapered from end to end, or otherwise arranged to engage a pipe, such as a lead-pipe, or an iron water pipe.

2 indicates the main body or shell, which is made detachable from the fixed portion 1, in any preferred manner although I here show it threaded into the end of said fixed portion. The shell 2 is provided with the usual discharge spout or opening 3, which may be made to assume various forms for various purposes, such for instance as that here shown, which is adapted for use when the device is applied with its stem in a horizontal position, and used as a water-faucet for a wash-basin or a sink, while if the stem be located in a vertical position, the form of the spout should have the contour indicated by dotted lines in Fig. 1. The shell 2 is made hollow, with a longitudinal passage 4 thereto communicating with the interior of the discharge spout 3. A straight stem 5 is mounted in the longitudinal passage in a manner which will permit it to be longitudinally reciprocative and axially revoluble. One end of the stem 5 projects outward through the shell 2 and its free

50 outer end is provided with any known form of operating handle or knob, or it may be a le-

ver, which I will designate by the numeral 6. Leakage past the exterior of the stem 5 is prevented by any ordinary stuffing box 7, formed upon the said shell so that said stem will work 55 therethrough.

The end of the shell opposite the stuffing box 7 is provided with a cylinder 8, one end of which is formed integral with or attached to said shell and the opposite end of which is 60 free and projects within the interior of the fixed portion 1 a considerable distance beyond the point at which said shell and said fixed portion are united, so as to form an annular space 9 around said cylinder. The cylinder 65 is constructed with its interior in a straight line, and in alignment with the stem 5. The interior of the bore of said cylinder is smooth. A series of radial perforations 10 are formed in said cylinder, preferably in the 70 form of an annular series at a point some distance from the free end thereof.

Mounted upon the inner end of the stand 5 is a valve or piston 11. This valve or piston I prefer to make in the form of a cup 75 constructed of leather or other suitable material. This cup is attached to said stem by means of a screw 12, passed centrally through it, and threaded into the end of said stem, a washer 13 being located upon said screw between the head thereof and the said cup. The cup 11 thus has its closed end next to the stem 5 and its open end adjacent the open free end of the cylinder 8.

The operation is as follows: Water or other 85 fluid entering the cock or faucet, passes inward in the direction indicated by the arrow, and fills the annular space 9 as well as the cylinder 8, but so long as the cup 11 and the stem 5 which carries it are in the position 90 shown by solid lines in Fig. 1, no water or fluid can pass by said cup, unless there be a leak, and the pressure will be exerted upon the open end of said cup and tend to spread it, thereby forming a tighter joint with the 95 interior of the said cylinder than existed prior to the exertion of such pressure. The pressure retains the cup and the stem always in normal position, which is that herein shown—that is, with the cup 11 located a greater distance from the free end of the cylinder 8 than the holes or apertures 10, so that when the

cup is in normal position no fluid can pass by it. When it is desired to permit the passage of fluid pressure is exerted upon the handle 6 with sufficient force to overcome the force of the pressure upon the cup 11, which will have the effect of moving said stem and said cup toward the free end of the cylinder 8, until said cup passes the holes or apertures 10 in the cylinder as indicated by dotted lines in Fig. 1. The holes or apertures 10 will thus be uncovered, and the fluid will have a free passage from the annular space 9 through said holes or apertures and into the longitudinal passage 4, and make its exit by way of the spout 3. Upon releasing the handle 6, the pressure of fluid upon the cup 11 causes it to resume its normal position.

14 indicates a suitable stop or shoulder located upon the stem 5 within the shell 4 and adapted to contact with said shell and limit the upward movement of said stem. The handle 6 contacting with the stuffing box 7, or a part of the shell, limits the downward movement of the stem. The shell 2 is preferably made detachable from the fixed portion 1 of the device, by providing the exterior of the cylinder 8 with a screw thread 16, and causing this screw thread to engage a thread formed upon the interior of the adjacent end of said fixed portion. This construction will permit said shell carrying the movable parts of the faucet to be readily detached for access to the cup 11, and for cleaning purposes, &c.

35 The construction above described is such that a self-closing faucet is provided, in other words there is during use such a predominance of pressure at all times upon the open end of the cup 11 as to normally retain same in a closed position. This "self-closing" function may be more or less marked, according to the construction of the parts. For instance, if the total area of the openings or perforations 10 is equal to the area of the open end of the cup 11, there will be no predominance of pressure upon said open end of said cup, when it is located in an open position, between the apertures 10 and the free end of the cylinder 8, for the reason that with 40 the cup in such position the pressure upon both sides of it or both ends of it is about equal. But if the combined area of the openings or perforations in the cylinder is considerably less than the area of the open end of said cup, a comparatively quick operating self closing faucet will be provided. In this latter case, I provide improved means for retaining the faucet in an "open" position, as follows: I make the stop 14 in the form of a 45 pin driven into a transverse aperture formed in the stand 5 so that its opposite ends will project, and when it is desired to lock the stem and valve at the limit of their inward movement, said stem is rotated a slight distance until one of the projecting ends of said 50 pin engages a web or projection 15 projecting upon the inner surface of the shell in the path

of said pin. A reverse movement, or a further rotation of said stem releases the pin from said projection 15.

I am aware that a water-bib has been constructed with an internal nozzle provided with a series of apertures arranged to be closed by a leather valve which reciprocates within said nozzle, and provided with means which limit the downward movement of said valve within said nozzle, so that said valve can pass beyond said apertures in one direction, but is prevented from passing beyond them in an opposite direction. But, in such construction the normal position of the valve is in contact with such apertures, and I therefore make no claim to such construction.

I am also aware that when a relief cock has been constructed with two valves seating in the same direction within a shell or casing and mounted upon a push-bar, and the push bar having at one end a spring and having on it a projecting pin adapted to engage in an L-slot in the casing for locking said valves in an open position, and I make no claim to such construction.

What I claim is—

1. An improved cock or faucet, having a fixed tubular portion 1, a shell 2 provided with a discharge spout or opening 3 and with a longitudinal passage 4 communicating with the interior of said discharge spout, a straight stem 5 mounted in the longitudinal passage to reciprocate longitudinally and revolve axially therein, one end of said stem projecting outward through said shell, a knob or handle 6 located upon the outer end of said stem to form a stop to limit the inward movement of said stem, a stuffing-box 7 formed upon said shell so that said stem will work therethrough, and with which said knob contacts to limit the inward movement of said stem, a cylinder 8 having its inner end secured to said shell and having exterior screw-threads adjacent 100 said end, said fixed portion being internally screw-threaded and mounted upon said cylinder, the opposite end of said cylinder being free and projecting within said fixed-portion a distance beyond the point at which said shell and said fixed-portion are united, so as to form an annular space 9 around said cylinder, said cylinder having a series of radial perforations 10 formed therein at a point some distance from its free end, a valve or 105 piston 11 mounted upon the inner end of the stem 5 and made in the form of a cup, a screw 12 passed centrally through said cup and threaded into the end of said stem, the closed end of said cup being next adjacent said stem and its open end adjacent the open free end of said cylinder, and a stop fixed upon said stem to limit the outward movement thereof and permit said valve to pass and rest entirely out of contact with said perforations when moving in one direction, said knob 110 6 permitting said valve to pass across said perforations and entirely out of contact therewith and upon the opposite side thereof when

said stem is pushed inward to the limit of its inward movement, whereby said valve at no time is stopped in contact with said perforations, said cup or valve being located a greater distance from the free end of said cylinder than the said perforations, substantially as herein specified.

2. An improved cock or faucet constructed with a shell 2, a stem 5 longitudinally reciprocative and axially revoluble in said shell, a cylinder 8 having one of its ends attached to said shell and its opposite end free, said cylinder having an annular series of radial perforations 10 formed therein at a point some distance from its free end, a valve mounted upon said stem in said cylinder and adapted to engage the same at points on opposite sides of said annular series of perforations, means which hold said valve normally out of contact with said perforations, a pin 14 driven

into a transverse aperture formed in the stem 5 so that its opposite ends project on diametrically opposite sides of said stem, means for limiting the inward movement of said stem and valve after said valve passes out of contact with said perforations, and a web or projection formed upon the inner surface of said shell in the path of said projecting ends of said pin, to be engaged by said ends to lock said stem and valve at the limit of their inward movement and hold same thereat with said valve out of contact with said perforations, substantially as herein specified. 25

30 In testimony whereof I affix my signature in presence of two witnesses.

THEODORE BONROE.
